DESIGN FOR A CONTAINER COVERING OF PAPER OR SIMILAR FLAT MATERIAL

Arthur S. Allen, New York, N. Y., assignor to
Berkshire Knitting Mills, Wyomissing, Pa., a
corporation of Pennsylvania

Application November 27, 1942, Serial No. 108,892

Term of patent 14 years

To all whom it may concern:

Be it known that I, Arthur S. Allen, a citizen of the United States of America, residing at New York, in the county of New York and State of New York, have invented a new, original, and ornamental Design for a Container Covering of Paper or Similar Material, of which the following is a specification, reference being had to the accompanying drawing, forming part thereof.

The drawing figure illustrates a container cov-

ering of paper or similar flat material showing my new design. It is understood that the surface ornamentation shown may be applied to any flat sheet material.

I claim:

The ornamental design for a container covering of paper or similar flat material, as shown and described.

ARTHUR S. ALLEN.
